UNITED STATES PATENT OFFICE.

TORE G. E. LINDMARK, OF STOCKHOLM, SWEDEN.

ELASTIC-FLUID TURBINE.

SPECIFICATION forming part of Letters Patent No. 737,121, dated August 25, 1903.

Application filed May 7, 1902. Serial No. 106,293. (No model.)

To all whom it may concern:

Be it known that I, TORE G. E. LINDMARK, a subject of the King of Sweden and Norway, residing at Stockholm, Sweden, have invented a new and useful Improvement in Elastic-Fluid Turbines, of which the following is a specification.

The invention relates to turbine-wheels actuated by any suitable elastic fluid, and more particularly to steam-turbines.

In the accompanying drawings, Figure 1 is a vertical section of my reversible steam-turbine, its casing, and connections. Figs. 2 and 3 are partial cross-sections, enlarged, on the lines, respectively, *a a* and *b b* of Fig. 1. Fig. 4 shows on the left-hand side the interior face of the left-hand portion of the casing with the wheel removed, the view being in the direction of the arrow in Fig. 1, and on the right-hand side a half-section on the line *x x* of Fig. 1. Fig. 5 is a section of some of the wheel-buckets on the line *y y* of Fig. 6. Fig. 6 is a section of said buckets on the line *z z* of Fig. 5.

Similar characters of reference indicate like parts.

1 is a steam-turbine wheel mounted upon the shaft 2, which shaft is journaled within the casing 3. Said casing is made in two parts, bolted together in any suitable way at the meeting flanges 3 and is supported by the standard 4. On shaft 2 is any suitable coupling 5 for transmission of power. The wheel-body is solid and has on its periphery buckets 6 and 7, secured thereto in any suitable way. Each of these buckets consists of a stem or shank portion *c*, provided at one end with two recesses *d e*, which recesses face in opposite directions. When the buckets are in place upon the wheel, the recesses *d* form a tier 6 and recesses *e* form a second and inner tier 7. Inasmuch as the wheel is rotated by fluid-jets directed upon the buckets, it will be evident that a jet directed into the recesses of tier 6 will actuate the wheel in the opposite direction to that in which a jet directed into the recesses of tier 7 would actuate it.

I will now describe the construction whereby the fluid is directed into either tier 6 or 7, as desired.

8 is the main steam-pipe from any source

of supply, which connects with two branch pipes 9 and 10. Pipes 9 and 10, respectively, communicate with annular chambers 11 and 12 in the casing 3. Seated in pipe 9 is a pivoted valve 13 and in pipe 10 a similar valve 14. Said valves are turned to open or close them by levers 15 and 16. The lever 15 on valve 13 terminates in a handle 17. The end 60 of lever 16 on valve 14 is pivoted to a link 18, which at its opposite extremity is pivoted to lever 15. The valves 13 and 14 are to be so set that when valve 13 is opened valve 14 is closed, and vice versa. Hence by means of 65 the handle 17 one valve can be opened and the other closed, depending upon the movement of said handle in one or the other direction, and in this way steam may be admitted into annular chamber 11 or annular 70 chamber 12 at the will of the operator.

Around the inner wall 19 of annular chamber 11 are arranged a number of nozzles 20, one of which is shown in cross-section in Fig. 2. These nozzles are preferably of the well-known De Laval type—that is, approximately conical—with their larger openings placed to deliver jets tangentially to the wheel-buckets. The several jets from these nozzles 20 are directed upon the inner tier of buckets 7. 80 After impinging on said buckets, and so setting the wheel in rotation, the jets pass between said buckets to the annular chamber 21 in the opposite side of the casing 3, and so to the branch pipe 22, which communicates 85 with the main exhaust-pipe 23. Similarly arranged in the inner wall 24 of chamber 12 are nozzles 25, Fig. 3, like nozzles 20, but turned in the opposite direction. These, however, deliver their jets upon the other 90 tier of buckets 6, and after impact upon the concavities in said buckets, thus setting the wheel in rotation in direction opposite to that in which it is impelled by the jets from nozzles 20, said jets pass between the buckets to 95 the annular chamber 26 in the opposite side of casing 3, and so to the branch pipe 27, which communicates with the exhaust-pipe 23.

The operation of the entire device will now readily be followed: If the handle 17 is operated to open valve 13, and hence simultaneously to close valve 14, steam will pass by pipe 9, chamber 11, nozzles 20, and buckets 7 to chamber 21, pipe 22, and main exhaust

23, and the wheel 1 will be set in rotation. In order to reverse the direction of revolution, the handle 17 is moved to shut the valve 13 and open the valve 14. Then the steam 5 proceeds by way of pipe 10 to chamber 12, nozzles 25, buckets 6, chamber 26 to branch pipe 27 and main exhaust 23. Hence by simply moving the handle 17 in one direction or the other the direction of rotation of the wheel 10 1 is controlled.

I claim—

1. The combination with the casing and its inlet and exhaust passages, of the turbine-wheel comprising a body and circumferential 15 buckets detachably secured to the periphery of the body and having oppositely-facing recesses.

2. A turbine-wheel comprising the body portion and circumferential buckets provided 20 with shanks secured to the periphery of said body and having oppositely-facing recesses.

3. A turbine-wheel comprising the body having peripheral recesses, and circumferential buckets provided with shanks fitting in 25 said recesses and having oppositely-facing recesses.

4. A turbine-wheel bucket having the shank *c* and recesses *d*, *e* therein.

5. In combination with a turbine-wheel 1 30 and buckets forming circumferential tiers 6, 7 of recesses thereon, the said recesses facing

in opposite directions, of the casing 3 having annular inlet-chambers 11 and 12 on opposite sides of said wheel, sets of nozzles 20 and 25 disposed in the walls of said chambers and 35 constructed to deliver fluid respectively to each of said tiers, valves 13 and 14 for controlling the admission of working fluid to said sets of nozzles, and means for simultaneously opening one of said valves and closing 40 the other.

6. A turbine-wheel having a body portion and circumferential buckets secured to said body and having oppositely-facing recesses at different radial distances from the center 45 of said body portion, substantially as described.

7. In a turbine, a wheel having a body portion and circumferential buckets secured to said body portion and having oppositely-facing 50 recesses at different radial distances from the center of said body portion, and a nozzle to direct motive fluid to the recesses in said buckets, substantially as set forth.

In testimony whereof I have signed my 55 name to this specification in the presence of two subscribing witnesses.

TORE G. E. LINDMARK.
